[57] CLAIM

The ornamental design for a cellular phone holder, as shown and described.

DESCRIPTION

FIG. 1 is a perspective view of a cellular telephone holder showing my new design;

FIG. 2 is a front elevation view thereof;

FIG. 3 is a top plan view thereof;

FIG. 4 is a side elevation view, with the opposite side a mirror image thereof;

FIG. 5 is a rear elevation view thereof; and,

FIG. 6 is a bottom plan view thereof.

The broken line showing of environment in FIGS. 1 and 2 is for illustrative purposes only and forms no part of the claimed design.
